UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

ADDRESS-PLATE.

1,122,839.

Specification of Letters Patent. Patented Dec. 29, 1914.

Application filed September 22, 1913. Serial No. 790,999.

To all whom it may concern:

Be it known that I, WILLIAM R. ALLEN, a citizen of the United States, residing at Cleveland, in the county of Cuyahoga and State of Ohio, have invented a certain new and useful Improvement in Address-Plates, of which the following is a full, clear, and exact description, reference being had to the accompanying drawings.

10 The object of this invention is to provide a cheap and effective address plate consisting of a holder and line slugs mounted therein. The line slugs carrying the items of the address may be cast or otherwise formed with a head portion and a longitudinal shank; the holder comprises a plate of suitable material having slots through which the shanks of the slugs project. The slots are provided with suitable lateral notches, and the shanks having corresponding lugs adapted to pass through such enlargements, the longitudinal shifting of the slug relative to the plate after such passage holding the slug to the plate. Suitable 25 means are provided to prevent the slugs becoming displaced when in their locked position.

The invention is hereinafter more fully explained and its essential characteristics 30 are set out in the claims.

In the drawings, Figure 1 is a plan of the holder alone; Fig. 2 is an enlarged perspective section of one of the line slugs alone; Fig. 3 is a bottom view of such slug; Fig. 4 is a cross section of the address plate; and Fig. 5 is a plan of the address plate.

Referring to Figs. 1, 4 and 5, A represents the holder for the slugs. This holder is a plate of comparatively thin material 40 and may conveniently be made of metal. Extending longitudinally of this plate are a plurality of parallel sided slots *a*, three being shown. Formed in the opposite edges of each slot are notches *a*¹, the notches of one slot being preferably staggered with reference to those of the adjacent slot.

B, in Figs. 2 to 5 inclusive, indicates the line slugs. They preferably consist of solid metal cast members having longitudinal shanks *b* with a laterally extending T-head *b*¹. On opposite sides of the shank near the lower edge thereof are lugs *b*². The shank *b* is slightly narrower than any of the slots *a*, and the lugs *b*² are slightly 50 smaller than the notches *a*¹. I find it con-

venient to make these lugs of a rounded or semi-cylindrical form and to shape the notches accordingly. The space between the upper faces of the lugs and the lower face of the T head is slightly larger than 60 the thickness of the plate A. Such slug as described is mounted in the plate A by being placed with the lugs *b*² in registration with any of the notches *a*¹ when the shank is pressed into the slot to bring the lugs on 65 the lower side of the plate, after which the slug is slid longitudinally approximately half the distance between adjacent notches *a*¹. This brings the lugs *b*² beneath solid spaces of the plate. When the slug is in 70 place, it is held against longitudinal shifting by any suitable means, as, for example, spring clips C sprung into the slots and frictionally engaging the walls thereof and abutting the ends of the slug. Such clips 75 may, if desired, be of the form shown in Patent No. 1,031,447, granted to The American Multigraph Company as assignee of Ferdinand Hohenberger.

My address plate may receive the printing pressure on the shoulders *b*¹ of the slugs and thence through the plate to a suitable support, or the slugs may stand on their own feet and the plate be simply to retain them in position. The lower faces of the 80 lugs *b*² are preferably flush with the bottom of the shank *b*, as shown in Fig. 3, so that there is a base of sufficient size to conveniently support the slug, if it is desired to have it stand on its own bottom. It is important that the slug stand accurately the desired height-to-paper, and, to avoid the expense of accurate machine work, I prefer to have it stand on an original cast surface; that is to say, if it stands on its own 85 bottom such bottom is in an original cast plane and the groove provided by the head and the lugs may be made in any convenient manner, by casting, or machining, or part casting and part machining. On the other 90 hand, if the printing surface is received by the head of the slug onto the plate, then the under face of the head is preferably an original cast surface and the lower portion of the slug may be formed in any convenient 95 manner.

The various notches *a*¹ in the plate and the lugs *b*² of the slug are both spaced equidistant so that the slug may be presented to various parts of the slot and have its lugs 100

pass through notches. By rounding the lugs and making the notches of corresponding shape, the plate may be conveniently punched. By staggering the notches of one slot with reference to the next, the slots may be brought as close together as desired without unduly weakening the plate.

Having thus described my invention, what I claim is:

- 10 1. The combination of a plate having a plurality of parallel slots, said slots being provided with lateral notches, the notches of one slot being staggered with relation to those of the adjacent slot, and slugs having shanks adapted to occupy the slots and provided with lugs adapted to pass through the notches and thereafter stand opposite portions of the plate between notches.
- 15 2. The combination of a plate having a plurality of parallel slots through it,

notches in the opposite edges of the slots, said notches being equi-distant and the notches of one slot being staggered with reference to those of the adjacent slot, slugs having heads and shanks, the shanks occupying the slots and being provided with laterally projecting equi-distant lugs adapted to pass through the notches and thereafter stand beneath material of the plate between notches, and means for preventing the slugs in this position from shifting longitudinally.

In testimony whereof, I hereunto affix my signature in the presence of two witnesses.

WILLIAM R. ALLEN.
